UNITED STATES PATENT OFFICE

WALTER E. BISCHOFF, OF ST. LOUIS, MISSOURI, ASSIGNOR TO RAWLINGS MANUFACTURING COMPANY, OF ST. LOUIS, MISSOURI, A CORPORATION OF MISSOURI

ATHLETIC GUARD

Application filed December 2, 1929. Serial No. 411,080.

This invention relates to guards of the kind that are used by athletes, for protecting a part or parts of the user's body from injury while the user is engaging in an athletic event, for example, a game of football. It relates particularly to thigh guards and shin guards of the type that are formed principally from fibre board or other relatively hard, non-metallic sheet material, bent or shaped so as to conform approximately to the outline of the part of the user's body which the guard is designed to protect.

One object of my invention is to provide a snug fitting, comfortable athletic guard formed principally from fibre board or other relatively hard sheet material bent or shaped to conform approximately to the part which the guard is designed to protect, and provided with a metallic reinforcing means arranged in such a manner that in the event it becomes broken or ruptured, it cannot cause injury to the user of the guard or to a person or object that strikes against the guard.

Figure 1 of the drawings is a front elevational view of a thigh guard constructed in accordance with my invention.

Figure 2 is a rear elevational view of said guard, partly broken away so as to more clearly illustrate the metallic reinforcing means.

Figure 3 is a vertical longitudinal sectional view, taken on the line 3—3 of Figure 2, looking in the direction indicated by the arrows; and

Figure 4 is a horizontal sectional view, taken on the line 4—4 of Figure 2, looking in the direction indicated by the arrows.

As illustrated in the accompanying drawings, my improved guard is composed of two or more pieces A and A' of fibre board or other suitable non-metallic sheet material bent or shaped so as to form a member of substantially oblong shape in general outline which is curved transversely or of substantially half round shape in horizontal cross section, so as to conform approximately to the shape of the user's thigh. At the peripheral edge of the guard is a binding B formed preferably from a piece of heavy felt that embraces the edge portions of the fibre

members A and A' and which is held in position by one or more rows of stitches 1 that also serve as a fastening means or securing means for the members A and A' which prevents said members from separating or from moving relatively to each other. The binding B is thick enough so that it will serve as a pad which effectively prevents the edges of the fibre members A and A' from cutting into the user's thigh, or from cutting through the user's garment in the event the guard is arranged in a pocket, on the inside of the leg portion of a pair of football pants, as is the conventional way of using the guard.

One or more metallic reinforcing devices C are arranged transversely of the guard between the fibre members A and A' so as to prevent said members from flattening out or changing their shape in the event the guard is subjected to a severe shock or blow, or in the event the fibre members become wet. In the form of my invention herein illustrated each of the metallic reinforcing devices C consists of a strip of steel bent so as to conform to the cross sectional shape of the guard and rigidly connected to one of the fibre members, for example, the inner member A' by rivets 2 located adjacent the ends of said strip, as shown in Figures 2 and 3. In constructing the guard the reinforcing devices C, after being bent to proper shape, are permanently and rigidly connected to the curved inner member A' of the guard, and said inner member is then arranged in nested relationship with the outer member A of the guard, thereby causing the metallic reinforcing devices to be completely housed and protected by the two fibre members A and A' between which said devices are interposed. Thereafter, the binding B is applied to the edge portions of the members A and A' and secured in position by means of stitches 1 which connect the members A and A' together and effectively prevent said members from separating or moving relatively to each other in any direction. I prefer to cut the members A and A' in such a way that when said members are combined the grain of one member will cross or be disposed at an angle to the grain of the other member, thereby

producing a laminated structure in which the sheets of material that constitute the body portion of the structure tend to reinforce and strengthen each other.

5 An athletic guard of the construction above described will retain its shape, even when it becomes wet, or when it is subjected to a severe shock or blow, due to the fact that it is composed of two curved pieces of fibre board or other suitable hard sheet material that are reinforced and strengthened by shaped strips of steel arranged transversely between said pieces and permanently anchored to at least one of said pieces. Such a guard is comfortable to the user, as it fits snugly to the part which it is designed to protect and is provided at its peripheral edge with a pad that encases or embraces the edge portions of the fibre members A and A'. One of the 10 chief advantages of such a guard, however, is that the metallic reinforcing means of same is effectively protected from moisture or dampness by the fibre members A and A', and is prevented from causing injury to the 15 user or to a person or object which strikes against the guard, in the event said metallic reinforcing means breaks or ruptures when the guard is in use, this being due to the fact that the metallic devices C are housed between two tough members that form the inner and outer surfaces of the guard.

While I have herein illustrated my invention embodied in a thigh guard that is intended to be positioned in a pocket formed in the leg portion of a pair of football pants, I 20 wish it to be understood that my invention is applicable to other kinds of athletic guards and that it is immaterial what means is used for maintaining the guard in operative relationship with the part of the user's body which the guard is designed to protect.

Having thus described my invention, what I claim as new and desire to secure by Letters Patent is:

45 1. A thigh guard, composed of two members curved in transverse cross section, constructed of fibre board and arranged in nested relationship, shaped strips of steel arranged transversely of the guard between said members, means for attaching said strips to the inner member, and a binding arranged to embrace the peripheral edges of said members and secured to same by stitches which also connect the peripheral edge portions of said 50 members together.

2. An athletic guard, composed of a plurality of shaped pieces of fibre board arranged in nested relation with the grain of one piece disposed at an angle to the grain of an adjacent piece, and a metallic reinforcing means arranged wholly on the interior of the guard between said pieces.

3. An athletic guard composed of a plurality of members curved in transverse cross section and arranged in nested relation, said

members being formed of relatively hard, non-metallic sheet material, and a metallic reinforcing means arranged wholly on the interior of the guard between adjacent curved members and attached to one of said members. 70
